UNITED STATES PATENT OFFICE

2,680,661

EXTENSIBLE TABLE TOP LATCH ELEMENT

Emil Bob Bremer, Alameda, Calif.

Application December 26, 1951, Serial No. 263,182

1 Claim. (Cl. 311—67)

1

This invention relates to household furniture such as card and breakfast tables where it is desired to extend the size of the table top, and in particular an extensible top having a square center panel with triangular shaped panels hinged to the edges and adapted to fold to nested positions upon the square panel.

The purpose of this invention is to provide a table top in which the size thereof may be increased without separate leaves or slides.

With the conventional type of breakfast or dining room table where the end sections are connected with sliding rails the parts are subject to swelling due to atmospheric conditions which make operation thereof difficult and where sections at the sides of tables hang downwardly when not in use they interfere with the legs of a person in a chair at the side of the table. With this thought in mind this invention contemplates an extensible table top wherein the extending sections fold to convenient nested positions upon the table top where they are readily accessible and also where they do not interfere with usual use of the table.

The object of this invention is, therefore, to provide means for forming an extensible table top in which the elements for extending the sides of the table top are hinged to the edges thereof and are readily folded to nested position upon the table.

Another object of the invention is to provide means for extending the sides of a table top, such as a top used for card tables which permits normal use of the table.

A further object of the invention is to provide an extensible table top wherein the extending sections are folded to nesting position upon the table top, which is of a simple and economical construction.

With these and other objects and advantages in view the invention embodies a table top formed with a square panel and triangular shaped sections hinged to the edges of the panel with hinges embedded in the upper surfaces of the panel and extending sections and wherein means are provided for securing the extending sections in nested position upon the panel.

Other features and advantages of the invention will appear from the following description taken in connection with the drawings, wherein:

Figure 1 is a plan view of the table top with the parts in the extended positions.

Figure 2 is a view similar to that shown in Figure 1 with the expanding sections folded upon the table top.

2

Figure 3 is a cross section, on an enlarged scale, through the central part of the table top taken on line 3—3 of Figure 1 illustrating the positions of the locking members with the sections of the table top extended as shown in Figure 1.

Figure 4 is a similar section also on an enlarged scale taken on line 4—4 of Figure 2, illustrating the positions of the locking elements with the extending sections nested upon the table top.

10 Figure 5 is a section taken on line 5—5 of Figure 1 and showing one of the hinges connecting the extending sections to the table top, said hinge being imbedded in the upper surfaces of the extending sections and table top.

15 Figure 6 is a cross section through the table top showing the extending sections elevated slightly above the table top.

Referring now to the drawings wherein like reference characters denote corresponding parts 20 the improved extensible table top of this invention includes a center panel 10, triangular shaped corner sections 11, 12, 13 and 14, hinges 15, a locking pin 16 and spring actuated latch pins 17 and 18 which are slidably mounted in tubular casings 19 and 20, respectively and which are resiliently held with the ends thereof in grooves 21 and 22 of the pin 16 by springs 23 and 24.

The panel 10 is preferably square however, it may be made of different shapes and designs and, 25 as shown in Figure 1, the extending sections are shaped to nest upon the panels with the extended corners thereof located at the center of the panel when folded to nested positions upon the panel.

30 35 The hinges 15 are imbedded in the upper surfaces of the panel and sections, as illustrated in Figure 5, one plate 25 of each hinge being positioned in a recess 26 in the panel 10 and the complementary plate 27 being positioned in a recess 28 in one of the sections. The hinges are secured to the panel and sections with screws 29. With the hinges installed in this manner the upper surfaces of the hinges are flush with the upper surface of the table top and, using comparatively small hinges, the hubs of the hinges are substantially within the limits of the sides of the top.

The locking pin 16 is positioned in an opening 30 in the center of the table top and a cylindrical head 31 of the pin nests in a recess 32 with the upper surface of the head flush with the upper surface of the table top, as shown in Figure 3.

50 55 With the sections 11, 12, 13 and 14 in extended positions, the head 31 is positioned in the recess

32 and the pins 17 and 18 extend into the annular groove 21 of the pin.

With the sections 11, 12, 13 and 14 folded to nested positions on the table top, the head 31 of the pin is positioned in recesses 33 in the corners of the extending sections and the pins 17 and 18 extend into the annular groove 22 of the pin 16, as shown in Figure 4. The pin 16, therefore, provides means for locking the extending sections in the folded position and with the head 31 of the pin in the recesses 33 the upper surface of the head of the pin is flush with corresponding surfaces of the sections.

The latch pins 17 and 18 are provided with enlarged sections 34 and 35 that are slidably mounted in the tubes 19 and 20, respectively and with the parts positioned as shown in Figure 3 the pins 17 and 18 extend through openings in the ends of the tubes.

The pins are retained in these positions by the springs 23 and 24 and tension on the springs is adjusted by plugs 36 and 37 threaded in the ends of the tubes. The tubes 19 and 20 are secured to the under surface of the table top by screws 38.

The table top may be provided with legs as indicated by the dotted line 38 or the top may be supported by other suitable means.

With the parts as illustrated in Figure 6 the expanding sections 12 and 13 are partly folded upon the table top or panel 10 and the latching pin 16 is shown in an upwardly extended position before it is drawn downwardly into the locking position shown in Figures 3 and 4.

This table may be used with the extending sections folded upon the panels whereby a comparatively solid table top is provided, or the sections may be extended outwardly as illustrated in Figure 1 whereby a comparatively large table top is provided.

It will be understood that modifications within the scope of the appended claims may be made in the design and arrangement of the parts without departing from the spirit of the invention.

What is claimed is:

In a latch mechanism for an extensible table top, which comprises a panel having folding sections hinged to the edges whereby the sections are adapted to selectively fold outwardly top twice as large as the continuous square panel fold to nested positions upon said panel, the improvement comprising a locking pin having a cylindrical head and having spaced annular grooves in the surface with the first of said grooves spaced from said cylindrical head, the panel and also the corners of said the folding sections having recesses therein in which the cylindrical head of the pin is adapted to nest, respectively, cylindrical elements on the under surface of the panel, latch pins slidably mounted in said cylindrical elements and springs in said cylindrical elements positioned to urge said latch pins outwardly of the cylindrical elements, said cylindrical elements being positioned whereby the latch pins extend into the annular grooves of the pin thereby providing means for securing the locking pin selectively with the head positioned in the recess of the panel, or in the recesses of the folding sections with the sections nested upon the panel.
